(57) **CLAIM**

The ornamental design for a telephone, as shown and described.

DESCRIPTION

FIG. 1 is a front elevational view of a telephone body constituting a portion of my new telephone design;

FIG. 2 is a top plan view of the telephone body of FIG. 1; FIG. 3 is a rear elevational view of the telephone body of FIG. 1;

FIG. 4 is a bottom plan view of the telephone body of FIG. 1;

FIG. 5 is a left side elevational view of the telephone body of FIG. 1;

FIG. 6 is a right side elevational view of the telephone body of FIG. 1;

FIG. 7 is a front view of a handset constituting a portion of my new telephone design;

FIG. 8 is a left side elevational view of the handset of FIG. 7;

FIG. 9 is a rear view of the handset of FIG. 7;

FIG. 10 is a right side elevational view of the handset of FIG. 7;

FIG. 11 is a bottom view of the handset of FIG. 7;

FIG. 12 is a top view of the handset of FIG. 7;

FIG. 13 is a left side elevational view of an assembly of my new telephone design, showing both the telephone body of FIGS. 1-6 and the handset of FIGS. 7-12; and,

FIG. 14 is a front elevational view of the assembly of FIG. 13.

The telephone base and handset have been shown separately in FIGS. 1-6 and 7-12 for convenience of illustration.
